(57) **CLAIM**

We claim the ornamental design for an optical block, as
shown and described.

DESCRIPTION

FIG. 1 is a perspective view of an optical block.

FIG. 2 is a side elevational view of the optical block, the
opposite side being a mirror image thereof.

FIG. 3 is a top plan view of the optical block.

FIG. 4 is a rear end elevational view of the optical block; and,
FIG. 5 is a front end elevational view of the optical block.
The bottom of the optical block forms no part of the claimed
design.
